UNITED STATES PATENT OFFICE.

PAUL HORACEK, OF PHILADELPHIA, PENNSYLVANIA.

HAIR CURLER OR CRIMPER.

Application filed December 9, 1927. Serial No. 238,934.

The present invention relates to an improved hair curler, crimper or waver, and the purpose of the invention is to provide an improved article of this kind, which is 5 extremely simple in construction and may be manufactured at a relatively low cost and sold at a reasonably low profit.

Another purpose is to provide a curler or waver, which will give the hair a substantial curl or wave, and due to the length of 10 the curler, the wave or curl in the hair will extend a substantial width, the process necessitating but a few curlers applied to the head of hair, to accomplish a complete wave over 15 the entire head.

Another purpose is to provide a curler or waver consisting of wire material of a resilient character comprising two opposed hingedly united members, one of the members having a loop for receiving a projection 20 of the other member, to lock the two members or jaws together, when the hair is entwined on one of the members or jaws, the member or jaw having the loop including 25 sides, which protrude through the member having the projection, so as to hold the hair in a crimped position on the curler, whereby when the curler is detached or removed from 30 the hair and the hair properly combed, the hair will fall in a symmetrical wave.

Still another purpose is to provide a two-part curler or waver, wherein one member or jaw is provided with eyes, which are so positioned so that by forming eyes on the 35 opposite member or jaw disposed at right angles to the first eyes, may engage with the first eyes and thereby afford a hinge connection between the two members or jaws, the first eyes being operatively and fixedly 40 connected so as to hold them in position, so that the two jaws will move in register with each other for the purpose of holding the hair tight on the curler.

Another purpose is to provide a curler, 45 wherein one of the jaws includes a fixed central member constructed from a single length of wiring with its loop and fastened within the projection of the two sides of the central member at its other end fastened 50 fixedly between the first eyes, to not only insure an additional and closer curl or wave to the hair, but also to brace the member or jaw, reinforcing the same in order to insure durability.

It is to be understood that the particulars 55 herein given are in no way limitative, and that while still keeping within the scope of the invention, any desired modification of details and proportions may be made in the construction of the appliance according to 60 circumstances.

The invention comprises further features and combination of parts to be hereinafter set forth, shown in the drawings and 65 claimed.

In the drawings:

Figure 1 is a view in perspective of the improved curler showing the jaws or members open.

Figure 2 is a view in perspective showing them closed, with the hair applied to one of the jaws, so that when the other jaw is forced up through the jaw carrying the hair, the hair will be crimped and caused to be waved when removed from the jaw. 75

Figure 3 is an enlarged detailed view of the pivotal connections between the jaws.

Figure 4 is a view of a modified form of curler, wherein the jaw which first receives the hair consists of two sides instead of 80 being reinforced with a central member, the jaws being opened.

Figure 5 is a perspective view of the form in Figure 4 showing the jaws closed with the hair applied. 85

Figure 6 is an enlarged plan view of the hinged connections between two jaws shown in Figure 5.

Referring to the drawings, 1 and 2 identify two jaws, the jaw 2 being constructed 90 of two pieces of wire material 3 and 4. The wire material 3 is relatively yieldable and forms the two sides of the jaw 2 which has a rectangular end 5, which is bent to form a loop 6 extending at an angle at the end. 95 This loop 6 constitutes a projection and is of circular formation, which extends between the sides of a U-shaped loop 7 of the jaw 1. The sides of the loop 7 ride over the grooved parts 8 of the projection or 100 loop 6, and fit partially into the crotches which adjoin the loop 6 and the end of the jaw 2.

The jaw 2 is relatively straight, while the sides of the jaw 1, while being parallel in 105 plan are slightly curved in side view, and the loop 7 of the jaw 1 is off-set relatively to the sides 9 of the jaw 1. The fact is

the sides of the jaw 1 when the two jaws are closed pass between the sides and the central brace (which is constructed from the wire material 4) so that when the hair is wrapped upon the jaw 2 relatively tight and the jaws closed, the hair will receive a pressing action which will result in creating a curl or wave in the hair when removed from the curler and is properly combed or 10 brushed. While it is herein described that the hair may be wrapped upon the jaw 2, it is obvious that it may be wrapped upon the jaw 1. The end portions of the sides of the jaw 1 converge toward each other and certain of the extremities of the jaw 1 terminate in eyes 11, which are interconnected with the eyes 12 of the sides of the jaw 2, in such a manner as to permit the jaws to move pivotally one toward the other. 15 20 In other words the eyes 12 are disposed in the same plane with the bends 13 at the ends of the sides of the jaw 2, while the eyes 11 are at right angles to the eyes 12, and furthermore the eyes 12 are rigidly fixed, by 25 brazing, spot welding or soldering, to the adjacent ends of the central brace 13, which is constructed from the wire material 4. This wire material 4 is bent upon itself as at 14 and is fastened in the projection or loop as 30 shown at 15. The sides of the central brace closely adjoin to insure rigidity of the jaw 2.

To give a curl or wave to the hair it may be wound upon the jaw 2 in the manner shown in the drawing, and then the jaw 2 35 is closed so that the jaw 1 will pass between the sides of the jaw 2. When the hair is removed from the jaw 2 and then properly combed a curl or wave is given the hair.

Referring to Figures 4 and 5 it will be 40 noted that the jaws are identical in construction, with the exception that the jaw 2 eliminates the central brace or reinforcement, and the eyes 12 of the jaw 2 are fastened together in any suitable manner preferably 45 spot welding or soldering or the like. Furthermore the jaws 1 and 2 in Figures 3 and 4 are narrower than the jaws in Figures 1 to 3 inclusive.

The invention having been set forth, what 50 is claimed is:

1. A hair curler or waver comprising a pair of opposing jaws, on one of which the hair may be wrapped, the other jaw having sides to protrude between the sides of the jaw 55 carrying the hair, the jaw carrying the hair having sides, the terminals of which at one end of said jaw having eyes disposed in a plane with the sides of such jaw, the jaw of which its sides protrude between the sides of 60 the other jaw, having its sides provided with eyes at right angles to and interconnected with the first eyes, whereby the two jaws are pivotally united, one of the jaws at its free end having a contracted loop with inclined 65 parts merging into the protruding sides, the

free end of the jaw on which the hair is wrapped terminating into a laterally projecting loop having a restricted neck, said last named loop adapted to engage between the sides of the first loop to a position approximating engagement with the reduced neck, to hold both jaws clamped together, with the sides of one jaw bearing against and causing the hair to crimp. 70

2. A hair curler or waver comprising a 75 pair of opposing jaws, on one of which the hair may be wrapped, the other jaw having sides to protrude between the sides of the jaw carrying the hair, the jaw carrying the hair having sides, the terminals of which at one end of said jaw having eyes disposed in a plane with the sides of such jaw, the jaw of which its sides protrude between the sides of the other jaw having its sides provided with eyes at right angles to and interconnected 80 with the first eyes, whereby the two jaws are pivotally united, one of the jaws at its free end having a contracted loop with inclined parts merging into the protruding sides, the free end of the jaw on which the hair is wrapped terminating into a laterally projecting loop having a restricted neck, said last named loop adapted to engage between the sides of the first loop to a position approximating engagement with the reduced neck, to hold both jaws clamped together, with the sides of one jaw bearing against and causing the hair to crimp, and a central longitudinal 85 brace with one end fixed between the horizontal eyes, the other end of the brace being fixed between the sides of the restricted neck of the second loop, thereby reinforcing the 90 jaw on which the hair is wrapped. 95

3. A hair curler or waver comprising a 100 pair of opposed jaws, on one of which the hair may be wrapped, the corresponding ends of both jaws being pivotally connected, the free portion of one of the jaws merging into laterally inclined parts, which terminate in a loop with parallel sides, whereby the sides 105 of such jaw may protrude between the sides of the other jaw to crimp the hair wrapped thereon, the free end portion of the other jaw terminating in a substantially circular loop with a restricted neck, the circular loop extending laterally and adapted to protrude between the sides of the first loop whereby the neck may engage with the sides of the first loop and retain the two jaws connected. 115

4. A hair curler or waver comprising a 120 pair of opposed jaws, on one of which the hair may be wrapped, the corresponding ends of both jaws being pivotally connected, the free portion of one of the jaws merging into laterally inclined parts, which terminate in a loop with parallel sides, whereby the sides of such jaw may protrude between the sides of the other jaw to crimp the hair wrapped thereon, the free end portion of the other jaw terminating in a substantially circular loop 125 130

with a restricted neck, the circular loop extending laterally and adapted to protrude between the sides of the first loop whereby the neck may engage with the sides of the first loop and retain the two jaws connected, a brace with one end fixed to the pivotal end of the jaw on which the hair is adapted to be

wrapped, the other end of the brace fixed between the sides of the restricted neck of the circular loop to reinforce the jaw on which ¹⁰ the hair is adapted to be wrapped.

In testimony whereof he affixes his signature.

PAUL HORACEK.
